FREEZER FOR MECHANICALLY OPERATED
REFRIGERATING UNITS

Fred Schaljo and Jack Miller, Detroit, Mich.

Application November 8, 1932, Serial No. 641,774

1 Claim. (Cl. 259—69)

The present invention relates to improvements in refrigeration and more particularly to the formation of ice creams and ices for table use in a domestic electrically or other form of mechanically operated refrigerating unit.

An important object of the invention resides in the provision of a so-called ice cream freezer to cooperate with an electrically or other form of mechanically operated domestic refrigerating units whereby upon insertion of the freezer within the refrigerating compartment, a connection is made between a motor and the freezer for operating stirring elements in the freezer.

Another very important object of the invention resides in the provision of an ice cream freezer of this nature which is simple in its construction, inexpensive to manufacture, thoroughly efficient and reliable in use, easy to manipulate, compact and convenient in its arrangement of parts, thoroughly efficient and reliable in use and operation and otherwise well adapted to the purpose for which it is designed.

With the above and numerous other objects in view as will appear as the description proceeds, the invention consists in certain novel features of a construction, and in the combination and arrangement of parts as will be hereinafter more fully described and claimed.

In the drawings:

Figure 1 is a front elevation of the apparatus embodying the features of our invention showing the same installed in a freezing compartment of a refrigerating unit.

Figure 2 is a vertical longitudinal section through the compartment showing the apparatus in side elevation.

Figure 3 is a detail vertical section through the gearing.

Figure 4 is a vertical section through the shafting from the electric motor.

Figure 5 is a vertical longitudinal section through the freezer.

Figure 6 is a view taken on the line 6—6 of Figure 2 looking downwardly.

Figure 7 is a view taken on the line 7—7 of Figure 2 looking in the direction of the arrow, showing the freezer casing removed.

Figure 8 is a similar view with the casing in place on the cover.

Figure 9 is a detail view of another cover.

Figure 10 is an end elevation of the stirrer.

Figure 11 is a perspective view of the stirrer shaft.

Figure 12 is a detail transverse section through the stirrer, and

Figure 13 is a sectional view taken substantially on the line 13—13 of Figure 2.

Referring to the drawings in detail it will be seen that the numeral 5 denotes a refrigerating element such as is used in electric, gas, and like mechanically operated domestic refrigerators and includes the freezing compartment 6. Numeral 7 denotes a rear wall of the refrigerator. The refrigerator is provided with the lower compartment 6 and an upper compartment 6a, the ceiling of the lower compartment 6 being denoted by the numeral 8. In the present instance there will be arranged in the upper compartment 6a the usual motor and compressor, and also, in the present instance there will be arranged in the upper compartment 6a a motor 9 mounted on brackets 10 rising from the ceiling 8. A bearing 11 is mounted in an opening in the ceiling to depend downwardly therefrom and has a packing box structure 12 associated therewith. A shaft 14 is journaled through the bearing and coupled as at 15 with the armature shaft 16 of the electric motor 9. Numeral 17 denotes a bearing bracket secured on the wall 7 and projecting forwardly therefrom and terminating in a bearing 18 through which the shaft 14 is journaled. A beveled pinion 19 is mounted on the bottom end of the shaft 14 and meshes with a beveled gear 20' on a shaft 20 which is horizontally disposed and journaled through a bearing 22 on an angular bracket 23 secured on the wall 7. A socket head 24 is fixed to the inner end of the shaft and has diagonal slots 25 in the sides thereof leading rearwardly from the forward edge thereof. Spring arms 26 are secured as at 27 to a block 28 which has mounted therein a bearing 29 through which said shaft 14 is journaled. This block is supported by a bracket structure 30 fixed to the wall 7. These spring arms 26 project forwardly along side of each other and have a bolt 31 connecting intermediate portions thereof adjacent clip jaw terminals 32.

Numeral 33 denotes a cylindrical casing having fixed thereto a supporting structure 34 adapted to rest on the bottom of the compartment 6. Numeral 35 denotes the outer end of the cylindrical casing which has a pet cock 36 mounted therein and a ring 37 movably engaged therewith by a bracket 38. The inner end of the casing 33 is closed by a cap 39 held in place by bolts 105 and nuts 40.

The bolts are pivotally engaged as at 41 on the casing 33 so that they may be swung into notched lugs 42 projecting from the edge of the cap 39. In Figure 5 it will be seen that a recess disk 43 is 110

threadedly engaged in a central opening provided in the cap 39. Agitator shaft 44 is journalled through the center of the recess disk 43. A disk 45 is fixed to the shaft 44 and a block 46 is disposed about the shaft 44 to extend into the recess disk 43 and has a recess to accommodate the disk 45. A cap 47 is threaded on the block 46 to hold packing material in a recess in the block as indicated at 50 to be disposed about the agitator shaft 44. The inner end of the agitator shaft 44 is pointed to extend in a recess in a block 51 mounted on the center of the inner face of the end 35. Within the casing there is mounted on the shaft 44 a plurality of agitator blades 52 which 15 extend longitudinally thereof and are twisted so that the forward edges are at angles of forty-five degrees with respect to the rear edge and these blades are transversely slotted as indicated at 53. The rear end of the shaft 44 has a cross pin 20 54 mounted therein so that this rear end may be inserted into the socket head with the pins in the notches thereof to be rotated by the gearing, shafting and electric motor previously described in detail. In order to hold the agitating shaft 25 in operative connection with these operating parts there is mounted on the cap 39 a head 55 with which the clip jaw terminals 32 engage and the tension of these jaws may be varied by the manipulation of the bolt 31.

30 When the proper ingredients have been placed in the casing 33 the agitator mechanism is inserted therein and the head or cap 39 secured in place as previously indicated. Then the freezer is inserted in the compartment 6 to engage the agitator shaft with the operating mechanism. After the current has been turned on, of course, the ingredients will be properly frozen as in any ordinary freezer and after proper time has been allowed for the freezing action, the freezer is 40 removed and the head or cap 39 is removed with the agitating or stirring mechanism and there is substituted therefore a cap 60 which has notched lugs 61 similar to the lugs 42 of the

cap 39 and then the casing may be replaced in the compartment and stored therein as long as desired.

It is thought that the construction, operation, utility and advantages of this invention will now 80 be clearly understood without a more detailed description thereof.

The present embodiment of the invention has been described in considerable detail merely for the purposes of exemplification since in actual practice it attains the features of advantage 85 enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described our invention, what we 95 claim as new is:

A refrigerator comprising upper and lower compartments, a motor located in the upper compartment, a shaft connected with the motor and passing into the lower compartment, means for 100 rotatably supporting the shaft, a horizontal shaft rotatably supported in the lower compartment, gears connecting the two shafts together, a slotted socket head connected to the horizontal shaft, spring jaws supported in the lower compartment, 105 and a container located in the lower compartment and having a projection thereon engaging the spring jaws when the container is placed in the compartment and being released by the jaws when the container is removed from the compartment, an agitator in the container including a shaft passing through a wall of the container, said shaft entering the socket in the head when the container is placed in the compartment and pins on the end of the shaft for engaging the slots 115 of the head when the shaft enters the head.

FRED SCHALJO.
JACK MILLER.
